UNITED STATES PATENT OFFICE

CARL E. HEYER, OF WEST ROXBURY, MASSACHUSETTS.

DESIGN FOR TYPE.

Specification forming part of Design No. 5,759, dated April 9, 1872.

I, CARL EMIL HEYER, of West Roxbury, county of Norfolk and State of Massachusetts, have invented and produced a new and original design for Printing-Types, of which the following is a specification:

The nature of my design, which I call "card-black," is fully represented in the accompany-

ing specimen impression, to which reference is made.

I claim as my invention—

The design for printing-types, as shown.

Witnesses: CARL EMIL HEYER.

DANIEL W. ROGERS,

ANNIE McMANAMY.
